UNITED STATES PATENT OFFICE.

FRANK B. HENDERSON, OF CHICAGO, ILLINOIS.

TABLE FOR INSTRUMENTS AND THE LIKE.

1,113,991.

Specification of Letters Patent.

Patented Oct. 20, 1914.

Application filed November 22, 1913. Serial No. 802,340.

To all whom it may concern:

Be it known that I, FRANK B. HENDERSON, a citizen of the United States, residing at Chicago, in the county of Cook and State 5 of Illinois, have invented certain new and useful Improvements in Tables for Instruments and the like, of which the following is a specification.

My invention relates to tables and the 10 like, and has for its primary object the provision of an improved device of this character wherein a glass top is firmly secured to and upheld by a metallic support.

With the above and other objects in view, 15 this invention consists substantially in the combination, arrangement, and construction of parts, all as hereinafter described, shown in the drawings which form a part of this specification and illustrate the preferred 20 embodiment of my invention, and more specifically set forth in the subjoined claims.

In the drawings:

Figure 1 is a top plan view of my invention; Fig. 2 is a bottom plan view thereof; 25 Fig. 3 is a vertical section taken approximately on the line 3—3 of Fig. 1 and looking in the direction indicated by the arrows; Fig. 4 is a fragmentary section on an enlarged scale, taken on the line 4—4 of Fig. 30 2, and looking in the direction indicated by the arrows; Fig. 5 is an enlarged view of one end of the section shown in Fig. 3.

Reference numeral 10 indicates generally the top of my improved table and is constructed of glass or other similar frangible material which may be easily rendered anti-septic. The top is surrounded by an upright flange 11, notched as at 12, the notches 12 receiving instruments laid upon the table 35 and preventing their movement regardless of the movement of the table. A plurality of ridges 13 is formed upon the top of the table, the ridges extending from a point adjacent the center thereof to a point adjacent 40 the edge. Preferably these ridges 13 are three in number, two being in line with each other and the third at right angles to the others. These ridges 13 are notched as at 45 14 for reception of instruments and are preferably of a height somewhat less than the height of the flange 11. Being composed of frangible material, it is essential that the top 10 be formed with a minimum of sharp corners or edges which would be easily chipped 50 or broken by contact with instruments inadvertently struck against them. For this

reason the meeting of the lower surface of the table top 10 with the outer surface of the flange 11 is rounded as at 15 (see Figs. 2, 3, and 5.) The top 10 is preferably given a 60 circular contour.

A downward extension 16 is formed upon the lower side of the top 10 and is preferably annular. For convenience in removing the top from the mold in which it is cast—if 65 made of glass—the peripheral surface of the extension 16 is beveled as at 17 (see Figs. 3 and 4). The table top is carried upon a branched support 18, upon the ends of the branches 19 of which is formed a band 20 70 of metal surrounding the extension 16, but slightly spaced therefrom. A layer 21 of elastic cement fills the space between the extension 16 and the band 20 and joins the top 10 securely to the support 18. By reason 75 of the elastic character of the cement layer 21 undue pressure upon the frangible extension 16 by the band 20 is avoided and the extension protected from breaking. The support 18 is vertically apertured preferably 80 below the center point of the top 10, as at 22, and a pin 23 bearing a spindle 24 positioned in the aperture 22 maintains the table in an upright position and permits rotation thereof. The pin 23 may be upheld in any 85 desired manner.

In the accompanying drawings and the foregoing specification is set forth the preferred embodiment of my invention, but it is obvious that one skilled in the art may 90 make modifications thereof without departing from the spirit of the invention.

I claim:

1. The combination of a table top, a downwardly tapering extension upon the lower side thereof, a support for the top provided with a band having a vertically disposed inner wall spaced from the extension, and a layer of elastic cement securing the band to the extension. 95

2. The combination of a table top formed of frangible material, a downwardly tapering extension of frangible material formed upon the lower side thereof, a support for the table top, a metallic band having a vertical inner wall surrounding the extension in spaced relation thereto, and a layer of elastic cement between the band and the extension securing them together. 105

3. The combination of a glass table top, a support therefor, a downwardly tapering glass extension formed upon the lower side 110

of the table top, a metallic band upon the support having its inner wall disposed vertical and surrounding the glass extension in spaced relation thereto and a layer of elastic cement positioned between the band and the extension, and securing them together.

In testimony whereof I have signed my

name to this specification, in the presence of two subscribing witnesses.

FRANK B. HENDERSON.
